UNITED STATES PATENT OFFICE.

WILLIAM HORCHLER, OF NEW YORK, N. Y., ASSIGNOR OF ONE-HALF TO GEORGE E. RODMAN, OF NEW YORK, N. Y.

AUTOMATIC STOP FOR RAILWAY-TRAINS.

1,127,248.

Specification of Letters Patent.

Patented Feb. 2, 1915.

Application filed February 25, 1914. Serial No. 821,071.

To all whom it may concern:

Be it known that I, WILLIAM HORCHLER, a citizen of the United States, residing at New York, in the county of New York and State of New York, have invented certain new and useful Improvements in Automatic Stops for Railway-Trains; and I do hereby declare the following to be a full, clear, and exact description of the invention, such as will enable others skilled in the art to which it appertains to make and use the same.

The present invention has relation to an improved means whereby a railway train may be conveniently stopped by automatic means whenever, through disability, carelessness or other cause, the engineer is about to pass a danger signal.

Some of the advantages of the invention are the following: Means are employed whereby the automatic stop is operated so long before the locomotive reaches the usual semaphore signal at the opening of a block that the train will be stopped before such signal is reached, thereby avoiding possible collision with a train which has stopped just after passing into the block. The engineer is given an opportunity to stop the train in the usual manner if he sees the signal, but, if he passes a point whence the signal should be seen, the automatic operation will take place. Another advantage of my device is that it is so constructed that the engineer can temporarily prevent operation of the automatic mechanism, as when it seems desirable to move slowly up to the beginning of the next block, or when entrance to a tunnel or passing under a bridge would act upon the mechanism. The parts are so arranged as to permit brakemen to walk along the center of a train without danger of being struck by the stationary operating arm, while, at the same time, the device does not occupy any extra room along the side of the train. The parts are simply arranged. They are compact and protected from interference by frost, etc. Further advantages will appear in connection with the following description having reference to the accompanying drawings wherein—

Figure 1 illustrates in partial elevation the relation of the engine and parts carried thereby to the block signal and stationary automatic operator respectively; Fig. 2 is a contracted diagram showing the relation of the successive stationary operators to their

respective block signals or semaphores, Fig. 3 is an elevation of the preferred arrangement of automatic parts on the locomotive cab, seen looking forward, Fig. 4 is a plan view of a preferred arrangement of the parts controlling the throttle of the engine, Fig. 5 is a side elevation of the parts shown in Fig. 3, the cab being shown in section, and Fig. 6 shows certain details in perspective.

My invention is capable of automatically controlling at once the throttle, the emergency air brakes, the whistle and a signal in front of the engineer or driver, and I have shown the preferred arrangement whereby all of these ends are accomplished. It is to be understood, however, that, except where expressly otherwise stated, in my claims, my invention is applicable to operation of any one or more of these ends.

In Fig. 2 are indicated, at 10 and 11, the usual block signals set at the beginning of two successive blocks and having the usual semaphore arms 12 and 13, or other suitable equivalents.

The tracks are represented at 14 and 15. Trains are supposed to move along said track in the direction of the arrow in Figs. 1 and 2. The general operating electric circuit or equivalent pneumatic system, whereby the block signals are operated in any usual manner is indicated at 15.

Placed at a suitable distance from each semaphore at the beginning of a block and on the side from which the semaphore is approached, are the stationary automatic operators including a stand or post 16, operating arm 17 and any well known semaphore arm operator controlled by a circuit 18 or equivalent means, whereby movement to danger of each arm 12, 13 will cause the operating arm 17 to move into position across the track as shown in Figs. 2, 3 and 5. The nature of this operating mechanism is not essential to the invention and is, therefore, left to the judgment of those skilled in the art. The essential point in this connection is that, when the semaphore arm at the beginning of a block is set for danger, the stationary automatic operator should be put into position to act upon the automatic mechanism on the train, substantially in the manner about to be described.

Upon the side of the top of the locomotive cab 19 (but not projecting laterally to an appreciable extent beyond the cab) is

mounted the external movable portion of the automatic apparatus forming the subject of this invention. In the preferred form shown this includes a normally upright contact arm 20 fixed to the end of a shaft 21 revolvably mounted upon suitable brackets 22, 23 fixed to the top of the cab. This arm is preferably provided at its outer extremity with a forked end 24 so placed as to come in contact with the stationary operating arm 17 when the same is placed for danger, and providing by the divergence of the sides of the fork for a considerable sway during travel of the locomotive. The upright position of the arm 20 is insured by a spring 25, one end of which is fixed to the bracket 23 and the other to a collar 26 fixed on the shaft. The limit of movement forward of the arm 20 is accomplished by the stop 27 which rests normally against a fixed shoulder 28 (see Fig. 5).

There is mounted loosely upon the shaft 21 a sleeve 29 carrying the arm 30 connected by a pivoted link 31 to a second lever 32 pivoted at 33 on the cab roof and extending into the cab, all as plainly shown in Figs. 3 and 5. The spring 34 is attached to the lever 32 and the sleeve 29 so as to keep said sleeve normally in the position shown in Fig. 5, that is to say, with the lower end of the lever 32 in the forward position within the cab. This lower end is connected pivotally by a connecting rod 35 with a bolt 36 normally entering an opening 37 in the flat extension 38 of the rod 39. This rod is guided by brackets 40 upon the forward wall of the cab and a spring 41 is attached to the bottom of the rod which tends constantly to pull it downward. One side of the sleeve 29 is shaped substantially as shown in Fig. 3 to act as a clutch member to coöperate with the second clutch member 42 of a well known type which is keyed to the shaft 21 as shown at 43 so as to turn therewith and to be capable of sliding thereon. This second clutch member can be thrown into and out of engagement with the sleeve 29 by means of a well known form of operating handle 44 pivoted in the roof of the cab at 45. I prefer to provide means such as the spring 46 tending constantly to keep the clutch 42 in engagement with the sleeve 29 so that if at any time, the shaft 21 is revolved by movement of the arm 20, the automatic mechanism will be operated. At the same time, since the handle 44 is within reach of the engineer or driver, he is able at any time to disconnect the shaft 21 from the operating mechanism so as to pass the stationary operating arm 17 where this is desirable, or to prevent stoppage of the train upon passage under bridges or tunnels which might otherwise act to stop the train.

In the preferred form shown wherein si-

multaneous operation is had of a number of agencies within the cab, the operating rod 39 is equipped and connected as follows: The cross arm 47 is fixed to the rod, one end of which is connected by an ordinary cord 48 with the whistle 49. The opposite end of the arm 47 is connected as shown with the slide 50 of a visible signal in front of the engineer. The second cross arm 51 is fixed near the lower part of the rod 39 and this arm has a lateral extension 52 extending over the locking mechanism of the throttle 53 to operate the same, preferably as follows: There are mounted upon the throttle lever 53, pivoted links 54 connected by the bar 55 pivoted to the ends of said links and from one of these links a pivoted connecting rod 56 extends to the ordinary well known securing bolt 57 which coöperates in a well known manner with the toothed sector 58 to lock the throttle bar 53 in any desired position. The spring 59 acts normally to push the throttle bar forward to shut off the steam from the driving cylinders. The opposite end of the cross bar 51 is adapted to operate the valve 60 of the emergency brake by means of a tripping mechanism as shown in Fig. 3.

It will be seen from the above that, in case the engine should pass a pre-determined point suitably fixed on the approaching side of the usual block semaphore set to danger, the arm 17 will push the arm 20 backward as indicated by the arrow and the dotted lines in Fig. 5, and thus rotate the shaft 21 which will act through the clutch 42 and sleeve 20 to liberate the rod 39. The spring 41 will cause the rod 39 to move sharply downward, thereby shutting off the steam, setting the emergency brake, and operating the signal within the cab. As hitherto stated it is within this invention to carry out one or more of these ends.

Any suitable means may be employed as is well understood to lessen shock between the arm 17 and the arm 20.

It is one of the advantages of my improvement that all external operating parts which might be subject to interference by frost, are inclosed as by the housing 61, and that the interior of such housing is connected by the openings for the levers 32 and 44 with the warm interior of the cab. This permits the warm air from the cab to sustain a proper temperature within the housing 61 so that frost cannot interfere with operation. The only opening to the outer air is that which admits the shaft 21 and this can, of course, be made relatively tight.

Various changes may be made in this device without departing from the scope of this invention and I do not limit myself to the details herein shown and described.

What I claim is—

1. A system for automatically stopping a

- 5 railway train before it passes a signal set for danger comprising in combination an external stationary operating device, a shaft revolubly mounted on the engine cab, an arm thereon adapted to be tilted by said stationary device, automatic means for stopping the engine within the cab, connections between said automatic means and said shaft including a movable clutch, and means within 10 in the control of the engine driver for operating said clutch, substantially as described.
- 15 2. In apparatus for automatically stopping a railway train, an external stationary operating device comprising an arm adapted to project over the side of the train, a shaft revolubly mounted upon the engine cab, an arm thereon adapted to strike said first named arm, automatic means within the cab 20 for stopping the engine, connections between said automatic means and said shaft including a movable clutch, and means on the cab for operating said clutch, substantially as described.
- 25 3. In apparatus for automatically stopping a railway train, an external stationary operating device comprising an arm adapted to project over the side of the train, a shaft revolubly mounted upon the top of the engine cab, an arm thereon having a forked
- end either branch of which is adapted to strike said first named arm, automatic stopping means for the engine within the cab, suitable operative connections between said shaft and said automatic means, and means 35 adapted to be manipulated from within the cab for rendering said connections temporarily inoperative, substantially as described.
4. In apparatus for automatically stopping a railway train, an external stationary operating device comprising an arm adapted to project over the side of the train, a housing on top of the engine cab communicating with the interior of the cab through an opening adapted to permit access of warm air to 40 the space within said housing, a revolubly mounted shaft within and projecting from one side of said housing, an arm thereon adapted to strike said first named arm, automatic stopping means within the cab operatively connected with said shaft, and means for temporarily rendering said connections 45 inoperative at will, substantially as described.
- 50 In testimony whereof, I affix my signature, in presence of two witnesses.

WILLIAM HORCHLER.
